Atty

UNITED STATES PATENT OFFICE.

FRED MORSE, OF NEW HAVEN, CONNECTICUT.

LIFE BELT.

Application filed July 7, 1922. Serial No. 573,263.

To all whom it may concern:

Be it known that I, FRED MORSE, a citizen of the United States, residing at New Haven, in the county of New Haven and 5 State of Connecticut, have invented certain new and useful Improvements in Life Belts, of which the following is a specification, reference being had therein to the accompanying drawings.

10 This invention relates to a life belt and it is the principal object thereof to provide mechanism of this character that may be inflated or deflated after being attached to the body.

15 Among other aims and objects of the invention may be recited the provision of a device of the character mentioned with a view to compactness, in which the number of parts are few, the construction simple, cost 20 of production small and efficiency and operation high.

The improvements in the details and arrangement of parts will be apparent from an inspection of the accompanying drawings 25 in connection with the description herein-after contained, wherein a preferred embodiment of the invention is disclosed for the purpose of imparting an understanding of the same.

30 In the drawings:

Figure 1 is a perspective view of a life belt constructed in accordance with my invention;

35 Figure 2 is a transverse sectional view of the valve mechanism;

Figure 3 is an underside view thereof; and

Figure 4 is a transverse sectional view thereof, taken generally upon line 4-4 of 40 Figure 2.

Having more particular reference to the drawings in connection with which like characters of reference indicate corresponding parts, 10 designates a belt, which is designed to go around the body of a person 45 and is constructed as is usual with such type of mechanism, the ends being secured by a button 11, or other similar fastening means, and connected therewith are suitable shoulder straps 12 to support the belt upon the shoulder, these being joined by a band 13.

The mechanism above described I do not claim as my invention, but as heretofore made it was necessary to inflate the belt before attachment to the body. Thus the belt should either be continuously inflated

and ready for use, or inflated when required just before use, in which case there is usually insufficient time for the purpose and during the excitement created by the exigencies 60 of the occasion it is often improperly and only partially inflated, thus impairing its efficiency.

My invention is applied particularly to the means whereby the belt may be placed 65 on the body and inflated afterwards, even though the wearer is in the water, an operation impossible of performance with a life belt of this type heretofore made. I accomplish this desirable result by applying 70 a rubber or very flexible tubing 14 to the belt 10 and securing to the end thereof a valve mechanism, which as shown herein consists of a body portion 15 having an outwardly flaring mouth piece 16, and in which 75 is secured a valve plug 17 having an opening 18 therethrough, which terminates at one end in a valve seat 19. Threaded into the lower end of the body portion 15 is a stem 80 plug 20 having a plurality of openings 21 therethrough.

Movably mounted in the body portion 15 is a valve 22 the stem 23 of which passes through and is supported in an opening 24 in the stem plug 20, a spring 25 surrounding 85 said stem and abutting at one end against said stem plug 20 and the other against the valve which exerts its tension so as to hold the valve against the valve seat 19. This valve is moved off its seat manually by 90 means of a lever 26 which projects through the radial slot 27 in the valve plug 17 and having a finger 28 upon its inner end, which rests against the top of the valve 22.

95 Suitable means may be provided for movably securing said lever, the means herein shown being a pin 29 which forms a pivot upon which the lever rocks when actuated through manipulation of that portion thereof that projects outside of the body 100 portion 15.

After the belt has been placed upon the body, assuming it to be in its deflated condition, the wearer grasps the tubing 14, 105 presses his finger against the outwardly projecting portion of the lever 26 and thereby forces the valve 22 off its seat and then fills the belt 10 with air through the mouth piece 16, the air passing through the opening 18, the body portion 15 and the openings 21 in the stem plug 20. When the belt has been 110 completely inflated the valve 22 is returned

to its seat, thus preventing the escape of air from the life belt when the lever 26 is released, the spring 25 thereafter maintaining said valve upon its seat.

5 Having described my invention what I claim as new and desire to secure by Letters Patent, is:

1. A valve mechanism comprising a body having a mouth piece at one end; a valve plug therein adjacent to the mouth piece and having a valve seat upon the inner face thereof; a stem plug closing the end of said body opposite to said mouth piece; and a valve movably mounted within said body 10 between said plugs; a pivotally mounted lever projecting through the wall of said valve plug and body and having contact at its inner end with said valve, whereby the same may be moved off its seat by manipulation of that portion of said lever that projects outside of said body member to permit air to pass thereby from the mouth piece.

2. In a device of the character described, a life belt; and means for inflating said life belt when the same has been applied to the

body and when both are in the water, comprising a flexible member connected with said life belt and a valve mechanism connected with said flexible member, said latter mechanism having a body with a mouth piece at one end thereof; a valve plug therein adjacent to the mouth piece and having a valve seat upon the inner face thereof, a stem plug closing the end of said body opposite to said mouth piece and having openings therethrough; a valve movably mounted within said body and supported in said stem plug; and a pivotally mounted lever projecting through the wall of said valve plug and body and having contact at its inner end with said valve, whereby the same may be moved off its seat by manipulation of that portion of said lever that projects outside of said body member to permit air to pass thereby from the mouth piece.

In testimony whereof, I have hereunto affixed my signature.

FRED MORSE.
